EXPANDING EARTH ANCHOR

Jasper Blackburn, Webster Groves, Mo.

Application September 22, 1930, Serial No. 483,417

15 Claims. (Cl. 189—92)

My invention relates to improvements in earth anchors, and has for its primary object an earth anchor of the expanding type which is so constructed that the greatest possible amount of 5 fluke surface can enter the ground around the hole.

A further object is to construct an earth anchor of the expanding type in such a manner that the outer sides of each fluke are supported by the base.

10 A still further object is to construct an earth anchor which is provided with guide ribs, thereby preventing a twist of the flukes.

Another object of my invention is to interconnect the spider and the expandible flukes of an 15 earth anchor, with separate link elements which can be readily inserted into said spider and fluke members without the aid of tools, and which when so placed in position will not accidentally become disengaged therefrom.

20 A still further object is to construct an earth anchor in which the under surface of each fluke is provided with sliding ribs, thereby greatly eliminating friction between the flukes and base as the flukes are forced outward.

25 In the drawings, Fig. 1 is an elevation of my device showing the anchor in collapsed position.

Fig. 2 is a top plan view of the same showing the guy rod in section.

Fig. 3 is a top plan view of the anchor expanded 30 with the guy rod and one of the links removed.

Fig. 4 is a top plan view of the base with the flukes removed.

Fig. 5 is a front view of one of the links.

Fig. 6 is a side elevation of the same.

35 Figure 7 is a side elevation detail of the central boss of the base.

Figures 8 and 9 are horizontal sections taken along the lines 8—8 and 9—9 respectively, of Fig. 7.

40 Figure 10 is a top plan view of the three flukes being assembled on the boss, the spider and links not being shown.

Figures 11 and 12 are perspective views of the upper and under sides respectively, of the upper- 45 most fluke.

In the construction of my device, I employ a base 9 which is preferably provided on its under side with a plurality of ribs 10. These ribs 10 tend to embed themselves in the earth at the bottom of the hole, thus preventing the base plate from turning. Extending upwardly and centrally of the base 9 is a central boss 11. This central boss is provided with a cylindrical opening 12 through which the guy rod 13 passes. The 55 guy rod is secured to the base 9 in any well known

manner. The upper end of the guy rod is provided with an eye 14 through which a guy wire is passed. This eye may be either formed integrally with the rod 13 or it may be secured thereon in any well known manner, this particular feature forming no part of my present invention.

The base 9 is also provided with a radially extending slot or groove 15 in which the guide tongue 16 formed on the underneath surface of the fluke 17 passes. Parallel to the guide 16 are ribs 18, 10 also formed on the underneath surface of the fluke 17 and which ride on the upper surface of the base 9. The fluke 17 is also provided with a substantially radially elongated slot 19 which surrounds the lower portion of the central boss 11. 15 The inner end of the opening 19 is closed so as to prevent the fluke from being driven off the boss during the expanding.

The base 9 is also provided with a projection 20 which has a central recess 21 and grooves 22; 20 the grooves 22 and recess 21 extending radially, the recess 21 receiving a guide rib 23 formed on the fluke 24 while the grooves 22 receive the slide ribs 25 formed on the underneath surface of the fluke 24.

25 The base 9 is also provided with an upwardly extending portion 26 provided with a central radially extending groove 27 and with an additional groove 28 to either side, the groove 27 receiving the guide tongue 29 on the flukes, while the 30 auxiliary grooves 28 receive the slides 31 formed on the fluke. Extending upwardly from each of the flukes is a socket 32 having an overhanging flange 50 to form an undercut portion therebelow, and with a laterally extending cut-out 51 through 35 said flange so as to provide an opening thereacross equal to the width of said undercut portion and leading into the latter.

Said socket is designed to receive the lower end of a link 34, while the upper end of the latter is 40 provided with a somewhat similar head 35 with a neck or groove 36.

Slidably mounted on the rod 13 is a spider 38, having a plurality of divergent arms which are preferably hollow so as to provide chambers 37 on 45 the underside thereof. Each of these chambers is provided with a top and a rear wall, and with substantially vertically extending spaced apart flanges or ribs 39, whereby the chamber thus formed is open along its bottom and front. Substantially horizontal flanges 40 project toward one another and extend substantially continuously from the bottom and front edges of the flanges 39 without a break, to thereby partially close up the underside of the front of the chamber, 55

or undercut the interior of the same as viewed from above the spider.

The links 34 are provided at their upper ends with the heads 35 and with a neck or groove portion 36 therebelow. It will be noted that the head portion is extended in opposite directions so as to overhang or project laterally beyond the groove or neck portion 36, as at 52, so that this end of the link may be readily inserted through the flanges and into the chamber 37 of the spider socket when the head is so positioned to bring the projections 52 into vertical alignment. The neck portion of the top end of the link is of such a thickness that it may be rotated within the chamber when said projections are within the chamber. After the head has been inserted within the chamber and then given a quarter turn, the projections 52 will overhang the horizontal flanges 40 and thereby prevent the link from pulling or dropping out of the socket. The head 35 may be flattened and narrowed thereacross so that the link may be readily inserted in to the chamber of the spider arm, in the manner just described.

The lower portions of the links are also flattened and formed with a reduced neck portion and oppositely directed pair of projections 33 therebeyond, somewhat similarly to the other end of the link, but it is to be noted that the projections at both ends of the link extend in the same directions, respectively, and that the head at the lower end of the link will pass into the socket 32 only when the link is in a predetermined position relatively thereto, the projections 33 passing into said socket through the cut-outs 51 only.

In inserting the links, the upper end is preferably first inserted, by rotating the link so that the upper head will pass interiorly of the chamber or socket between the opposed flanges 40, after which the link is given a quarter turn to place the projections 52 so that they overlie the flanges 40 and prevent the links from dropping out of the spider arm. The lower end of the link is then brought adjacent the respective socket 32, with the projections 33 registering with the cut-outs 51, and then a slight blow is given the lower end of the link when so positioned, to actuate the latter into the interior of the socket, and thus securing the lower ends of the links in position, all of which has heretofore been set forth in my co-pending application Serial No. 447,897, filed April 28, 1930, which became abandoned April 12, 1932.

In addition to the details of construction hereinbefore set forth, it is to be particularly noted that the arms of the spider and of the sockets 32 are provided with a convex bearing surface to provide additional bearing surfaces for the links. The underside of the arms of the spider 38 are rounded or formed with a convex bearing surface or flanges 41 on their lower forward edges, so that said convex flanges bear against the co-operating concave flanges 42 of the top heads of the links, below said reduced neck portions, to thereby provide what might be termed "radius bearings." The sockets 32 are similarly rounded at 43 to provide convex or arcuate radius bearings on which the arcuate or concave flanges or projections 44 of the lower ends of the links may ride. By this construction I obtain a wide bearing area at each end of the link, and which makes a much stronger connection between the links and their co-operating members.

It is to be noted that the boss 11 is not of uniform horizontal shape and cross-section, but

upon the contrary differs at different vertically spaced distances, so as to permit of a quick and easy assembling of the flukes thereon. As shown most clearly in Figs. 7, 8 and 9, the projecting part of the boss at the lowermost level is of substantially square cross-section as indicated at 53, the thickness of said squared section being approximately equal to the thickness of the lowermost fluke 17. The next adjacent cross-section of the boss is substantially circular, as at 54, of a height equal to the thickness of the next higher fluke 24, so that the fluke 24 may be rotated about the portion 54, while the fluke 17 is non-rotatable during assembly. The next higher adjacent portion of the boss is somewhat squared with rounded-off diagonally opposed corners, the flat sides being indicated at 55 and the rounded corners being indicated at 56. The uppermost portion 57 of the boss 11 is rectangular in cross-section, the width of the same being equal to the width across the flat sides 55 of the next lower portion, but the length being greater so that the ends project beyond the ends of the same.

It is to be further noted that the flukes have the radially elongated openings 19 of equal width, equal to or preferably slightly greater than the diameter of the circular section 54 of the boss, slightly greater than the width across the flat sides of the sections 53, 55, and 57, so that the flukes may be rotated about only the circular cross-section 54. The uppermost fluke 30 is provided with an enlargement 19c at one side edge of the opening 19 at some point intermediate the inner and outer ends of the latter.

In assembling the flukes upon the base, the lowermost fluke 17 is positioned so that its opening 19 is in alignment with the rectangularly elongated top end of the boss, and the fluke then dropped down, and then partially rotated until its rib or tongue 16 is in the guide groove 15 of the base. The next fluke is similarly dropped in place, with its under rib 23 in the groove 21. Finally, the uppermost fluke 30 is brought into position over the boss 11, as shown in Fig. 10, the enlargement 19c being adjacent the rounded corners 56 of the boss, and then this fluke 30 is partially rotated in said plane (and with the under flukes in expanded positions) so that the arcuate periphery of the fluke 30 substantially bears against the sockets 32 of the fluke 17, this rotation ceasing when the rib 29 of the fluke 30 is in alignment with the guide groove 27. In said last-mentioned position of the fluke 30, the projecting ends of the boss 11 overlie or overhangs the top surface of the fluke to either side of the opening 19.

After the flukes are thus assembled, the spider is placed on the rod 13, and the links 34 then manipulated, first by insertion of their uppermost ends into the spider sockets and then given a quarter turn therein, and then the lower ends are inserted between the ribs of the fluke sockets, in the manner hereinbefore set forth.

It will be noted from Fig. 3 that when the anchor is fully expanded, the ends 45 of each of the flukes project within the periphery of the base 9; in other words, the ends 45 of the fluke 17 rest directly on the base. One end 45 of the fluke 24 rests on the end 45 of the fluke 17, while the other end is supported on a projection 46 extending upward from the base 9. One end 45 of the fluke 30 in turn is supported by one end 45 of the fluke 24, while the other end 45 is supported on a projection 47 formed on one end of the fluke 17. In this way, all of the ends of the various

- flukes are firmly supported so that springing tendency of the flukes, when the anchor is expanded is greatly reduced, if not entirely eliminated.
5. It is to be understood, of course, that the flukes are expanded in the usual manner, that is, by striking the spider 38 with a tamping bar or tool for forcing it down and causing the links to move the flukes outward into the solid earth.
10. It is also to be understood that prior to placing the anchor, a hole is drilled into the ground by means of a boring tool; then when the proper depth of hole has been reached, the anchor is lowered to the bottom and then the flukes are 15 expanded, so as to be forced into the solid earth surrounding the hole, after which the hole is filled up.
- Having fully described my invention, what I claim is:—
20. 1. An earth anchor comprising a base, a guy rod secured to said base, a plurality of radially extensible flukes mounted on said base, sockets projecting upwardly from said flukes, a spider mounted for vertical movement on said guy rod, 25 links pivotally secured at their opposite ends in said spider and sockets, and ribs extending across the ends of said spider and sockets for providing a bearing surface.
2. The earth anchor of claim 1 in which the 30 under surface of the flukes is provided with means for preventing twisting of said flukes and with means for reducing the frictional area of the flukes on said base.
3. An earth anchor comprising a base, an upwardly projecting boss formed centrally of said base, a guy rod secured in said boss, a plurality of flukes mounted on said base, a spider slidably mounted on said guy rod, said spider having arcuate bearings formed thereon, arcuate bearings 35 formed on said flukes, and links for connecting said spider and flukes whereby said flukes are moved outwardly and having complementary arcuate bearings engageable with the bearings on said spider and flukes.
45. 4. An earth anchor comprising a base, an upwardly projecting boss formed centrally of said base, a guy rod secured in said boss, a plurality of flukes mounted on said base, a socket having an arcuate thrust bearing on each of said flukes, 50 a spider slidably mounted on said guy rod, said spider having arcuate thrust bearings formed thereon, and links having complementary arcuate bearings for engaging said bearings on said spider and flukes to interconnect the latter.
55. 5. An earth anchor comprising a base, a guy rod secured thereto, a plurality of flukes mounted on said base, means for supporting said flukes at their sides on said base, guide ribs between the under surface of said flukes and said base to prevent sidewise movement of said flukes thereon, a spider slidably mounted on said rod, additional ribs between said flukes and base to form a sliding surface of reduced area as compared with the entire opposed surfaces therebetween, to reduce 60 the frictional area between said surfaces as said flukes are moved outwardly, and links pivotally secured at their ends to the spider and flukes whereby the latter are moved outwardly when said spider is moved downwardly on the guy rod.
65. 6. An expanding earth anchor comprising a base, a guy rod thereon; a plurality of laterally extensible flukes on said base and provided with upwardly projecting sockets, a spider movable longitudinally on said rod, links pivotally secured 65 at their opposite ends in said spider and sockets of said base, and cooperatively engageable bearing ribs extending across the ends of said spider, sockets and links to provide bearing surfaces exteriorly of the ribs of said sockets and spider and take the thrust transmitted through said links.
7. In an earth anchor comprising a base having a central projection, a rod secured in said projection, a spider slidably mounted on said rod, a plurality of flukes adapted for radial expansion 10 on said base, and links connected between said flukes and spider and having means at their ends whereby one end must be positioned in said spider and then partially rotated before the other end may be secured to said fluke, and whereby said flukes are forced outwardly when the spider is moved downwardly.
8. In an earth anchor comprising a base, a rod secured on said base, a plurality of radially movable flukes on said base, a spider slidably mounted on said rod, said spider being provided with chambered arms, a link having a head carried by each of said arms and of minimum thickness when in a predetermined position so that said head may be inserted into the chambered portion when the head is so positioned only, and with projections to retain said head therein when the link is turned, and means carried by said flukes for securing the opposite ends of said links whereby said links are prevented from turning 15 and becoming detached from said spider.
9. In an earth anchor comprising a base, a plurality of flukes carried thereby, a rod in said base, a spider having chambered arms slidably mounted on said rod, said chambers having their bottom and front ends open, said openings being continuously of less width than the interior of said chamber, links provided with heads removably carried in said chambers, and a socket carried by each of the flukes for receiving the opposite end of one of said links.
10. In an earth anchor having a base, a rod secured thereto, a plurality of radially movable flukes located on said base, a spider slidably mounted on said rod, said spider having chambered arms, and links for actuating said flukes to expanded position, means for connecting said links and flukes and spider and including a head carried by each of said links, said chambers opening along their bottom and outer ends, said openings being of less width than the chamber, said link having flattened portions on said head so that the same can be readily inserted through the openings in said arm and into said chambered portion, said head also provided with shoulders for retaining the same in said chambered portion upon being turned, and means carried by said flukes for receiving the opposite ends of said links inserted thereinto, whereby said links are prevented from turning, and the heads thereof are retained in the chambered arms of the spider.
11. In an earth anchor the combination with a base, a rod and a plurality of movable flukes thereon, a spider slidably mounted on said rod, and sockets on said flukes and spider, of links interconnecting the spider and flukes for expanding the latter and having their ends insertable within said sockets, the opposite ends of said links being so shaped that they will enter their respective socket in a predetermined position only, and one end must first be inserted into its socket and then the link rotated a quarter turn about its longitudinal axis before the other end may be inserted into its socket.

12. An earth anchor comprising a base, a guy rod secured to said base, a central boss formed on the upper face of said base and surrounding said guy rod, a plurality of flukes mounted on said base, guide ribs formed on the undersurface of said flukes and engaging with said base for preventing side movement of said flukes, additional ribs on the under side of said flukes forming a reduced sliding surface between the same and said base, a spider slidably mounted on said guy rod, and links pivotally secured to said spider and flukes whereby said flukes are moved outwardly when said spider is moved downwardly.
13. An earth anchor comprising a base, a guy rod secured to said base, a plurality of flukes mounted on said base, means for supporting said flukes at their sides on said base when the latter are expanded, ribs on the under surface of said flukes for forming a sliding surface to reduce the frictional area of said flukes on said base, a spider slidably mounted on said rod, and links pivotally secured at their ends to said spider and flukes whereby said flukes are moved radially outwardly when said spider is moved downwardly on said rod.
14. An expandible earth anchor comprising a base, a guy rod thereon, a plurality of flukes

movable in unison laterally across said base and having link sockets, a spider movable on said rod and having link sockets, links connecting said sockets of said spider and flukes to actuate the latter laterally upon movement of the former, and arcuate bearing ribs on one of the ends of said links and the exterior of said co-operating sockets to take the thrust transmitted through said links.

15. An earth anchor comprising a base, a boss extending upwardly therefrom, a guy rod in said boss, a spider slidably mounted on said rod, a plurality of flukes movable slidably laterally on said base and each having an elongated slot through which said boss extends, said slots closed adjacent their inner ends to prevent movement of the flukes past the boss in one direction, and the uppermost fluke having said slot enlarged in width intermediate its ends to permit partial rotation of said fluke therewith about said boss to assemble said fluke on said boss, and links connecting said flukes and spider whereby movement of the latter longitudinally on the rod will transmit lateral movement to said flukes.

JASPER BLACKBURN.
